UNITED STATES PATENT OFFICE.

HALE W. DE JARNATT, OF CENTRALIA, MISSOURI, ASSIGNOR, BY MESNE ASSIGNMENTS,
TO THE MARLIN FIREARMS COMPANY, OF NEW HAVEN, CONNECTICUT, A COR-
PORATION OF CONNECTICUT.

MAGAZINE-FIREARM.

940,791.

Specification of Letters Patent. Patented Nov. 23, 1909.

Application filed April 4, 1906. Serial No. 309,896.

To all whom it may concern:

Be it known that I, HALE W. DE JARNATT, a citizen of the United States, residing at Centralia, in the county of Boone and State of Missouri, have invented certain new and useful Improvements in Magazine-Firearms, of which the following is a specification.

My invention relates to repeating firearms, and particularly to improvements in the cartridge cut-off mechanism for the magazine. That type of repeating firearm to which my invention relates includes a tubular magazine arranged parallel with and adjacent to the barrel and opening rearwardly into the receiver.

The object of the invention is to provide simple and effective mechanism whereby the user may at any time readily release all of the cartridges in the magazine to permit the latter to be completely emptied.

That type of magazine firearm with which my improvement is illustrated herein is fully set forth and described in United States Letters Patent No. 528,905 of November 6, 1894; No. 560,032 of May 12, 1896, and No. 776,322 of November 29, 1904. Since the action mechanism employed is set forth in detail in the above referred to patents, it will be unnecessary for me but to generally refer to the same herein, particularly as it is not absolutely essential to the present invention that that construction alone be employed in connection with my improved cut-off apparatus.

In the accompanying drawings Figure 1 is a side elevation on a reduced scale and partly in section of a magazine firearm containing my invention, the ends of said firearm being broken away. Fig. 2 is a relatively enlarged cross section on the line $x-x$ Fig. 1. Fig. 3 is a fragmentary view of the inside of one wall of the receiver, showing the cut-off. Fig. 4 is a section on the line $y-y$ of Fig. 3, looking up. Fig. 5 is a section on the line $z-z$ Fig. 3, looking up. Fig. 6 is a side elevation of the breech portion of a gun, showing fragments of the barrel magazine and stock, one side of the receiver being partly broken away and the locking bolt being removed. Fig. 7 is a fragmentary view of a part of the receiver, showing the breech-block and locking bolt in section, in the position in which the locking bolt appears just before the breech is locked.

Fig. 8 is a perspective view of the locking bolt. Fig. 9 is a view similar to Fig. 6, but showing the breech mechanism fully open. Fig. 10 is a side elevation of the carrier. Fig. 11 is an end elevation of the breech-block shown in Fig. 8.

In the drawings, 1 is the breech frame or receiver, 2 is the stock, 3 is the barrel and 4 is the magazine, the latter being arranged underneath the barrel and opening rearwardly into the receiver.

5 is a reciprocating breech-block guided in the frame 1 and actuated to and fro by suitable mechanism, such as the handle 6, which slides to and fro on the magazine. In the particular form of construction herein shown, which, as already stated, is merely preferable, this action handle 6 has a rod 7 extending rearwardly and entering the receiver, said rod being connected with a locking bolt 8 in the manner set forth in the above referred to patents. The locking bolt 8 is pivoted at 9 in the breech-block 5 and has a tilting action.

When the locking bolt is in the position shown in solid lines Fig. 7, the breech-block 80 is unlocked and may be moved to and fro. When, however, the locking bolt is tilted into the position indicated in dotted lines Fig. 7, it engages the receiver frame 1 at its rear end and the breech-block 5 at its 85 forward end, locking the same in a forward position. 8^a is a lug depending from the forward end of the locking bolt, with which the action rod 7 is directly connected. The first movement of the action rod in a rearward direction operates, through the lug 8^a, to tilt the locking bolt from its locking position (dotted lines Fig. 7) to the unlocked position (solid lines Fig. 7), and hence the last movement of the action rod in a forward direction is to tilt the locking bolt into the position illustrated in dotted lines Fig. 7. It is the tilting movement of the locking bolt and lug 8^a, as will hereinafter be seen, that is availed of for the purpose of mechanically operating the cut-off, in the preferred form of my invention. 10 is a tilting carrier operating in synchronism with the balance of the action mechanism, whereby at the proper time it will descend and receive a cartridge from the magazine and convey it up to the proper position in front of the retracted breech-block, whereby when

the latter advances said cartridge will be pushed into the barrel.

The parts thus far described are parts well known and more fully described in the above referred to patents.

My improved cut-off comprises a two-part device which is capable of mechanical or manual operation, said cut-off being mechanically operated during the regular manipulation of the action mechanism of the firearm to release the cartridges separately and successively from the magazine to permit them to be fed by the carrier. If at any time it is desired to release all of the cartridges from the magazine, the cut-off may be manually operated for that purpose. In the particular form shown, the cut-off comprises the two pieces or dogs 11 and 12 arranged side by side in a recess in the inner side wall of the receiver and pivoted upon a suitable bearing or pin 14. The forward end of the cut-off piece 11 stands slightly in advance of the forward end of the cut-off piece 12, and first engages each cartridge in the magazine. This piece 11 has a cam face or incline 11^a, which flares upwardly and inwardly relatively to the receiver. The piece 12 has a cam face or incline 12^a, which flares downwardly and inwardly relatively to the receiver. The shoulder 15 on the lug 8^a of the locking bolt stands between these two inclines when the parts are in the position indicated in Fig. 7, in which position, as before explained, the breech is closed, but the locking bolt has not yet been tilted by the last advance movement of the action rod 7. If it may be assumed a cartridge in the magazine is now bearing against the forward end of the part 11 (the forward end of this part, as well as the forward end of the part 12, now being held out under the influence of suitable springs indicated at 11^b—12^b, Figs. 4 and 5) it will be seen that when the locking bolt is tilted to the locking position (dotted lines Fig. 7), the part 15 on the lug 8^a will encounter the incline 11^a and press back the forward end of the part 11, thus permitting the cartridge in the magazine to move rearwardly slightly where it will be held by encountering the forward end of the part 12 of the cut-off, which now stands advanced. In this position the cartridge will remain until the part 12 is tilted.

16 is a finger-piece or button mounted in the side of the receiver for manual manipulation. This finger-piece bears against the rear end of the dog 12, whereby the operator may manually tilt said part 12 by merely pressing on the button or finger-piece 16. This tilting of the part 12 retracts the forward end thereof, and since when the gun is locked and closed the part 11 is repressed by the action mechanism, it follows that the cartridges in the magazine may freely escape whenever the button 16 is pressed in.

By this means the operator may at any time readily empty the magazine without the necessity of "pumping" the cartridges successively through the entire action, as was formerly the case. The forward end of the carrier moves in an arc slightly to the rear of the forward end of the part 12, so that in the regular operation of the gun in which the cartridges are to be fed successively to the barrel, the operation is as follows: The rearmost cartridge in the magazine rests against the forward end of the part 11. The locking of the gun represses this part and permits said cartridge to move back against the end of the part 12. The unlocking of the gun frees the part 11, which then presses against the rim of the cartridge resting on stop part 12. As the lug 8^a descends during the unlocking movement to release the forward end of the part 11, it simultaneously engages the incline 12^a and depresses the same sufficiently to let the cartridge engaged thereby move back slightly until it encounters the forward end of the carrier (which descends slightly with the lug), against which it is held until the carrier fully descends to permit said cartridge to slide back thereon to be elevated thereby into a position in front of the breech-block. As soon as the rim of this particular cartridge has moved back from engagement with the forward end of the dog 11, the latter of course springs forward under influence of spring 11^b so as to engage the next succeeding cartridge in the magazine. It will thus be seen that each cartridge has three distinct positions during each cycle of movement of the action mechanism before it is entirely free to move back into a position on top of the carrier.

From the foregoing it is apparent that the cut-off is operated mechanically during each cycle of operation of the action mechanism, and may be operated manually whenever the gun is locked to permit the magazine to be completely emptied. By this improved construction safety is guaranteed to the user, inasmuch as it is now unnecessary to pass the cartridges successively through the action mechanism in the regular manner whenever it is desired to empty the magazine after a day's shooting.

Having fully described my invention, what I claim as new and desire to secure by Letters Patent is:—

1. In a magazine gun, a frame, a magazine, a breech bolt, a locking bolt, dogs mounted in the frame to operate as cartridge stops, means for actuating the locking bolt whereby said locking bolt operates said dogs to permit the same to successively engage a cartridge as the same is being expelled from the magazine, one of said dogs projecting slightly ahead of the other and being arranged to engage the next succeed-

ing cartridge in the magazine and prevent its discharge therefrom when the first mentioned cartridge has been entirely removed from said magazine.

5 2. In a magazine gun, a frame, a magazine, a breech bolt, a locking bolt, two cartridge stop dogs mounted in the frame, means for actuating the locking bolt whereby said bolt operates both of said dogs.

10 3. In a magazine gun, a frame, a magazine, a breech bolt, a locking bolt, two cartridge stop dogs mounted in the frame, means for actuating the locking bolt whereby said bolt operates both of said dogs, and 15 a depending lug carried by the locking bolt and constituting a part thereof, said lug directly engaging said dogs in the act of operating the same.

4. A magazine gun comprising a frame 20 having a locking bolt therein, dogs mounted in the frame, said dogs adapted to engage the cartridges in the magazine, and means for operating the locking bolt whereby it releases one of the dogs and engages the 25 other in its movement thereby releasing a cartridge in the magazine, and the dog released by the bolt adapted to engage the next succeeding cartridge and retain it in the magazine.

30 5. A magazine gun comprising a frame, a locking bolt therein, dogs mounted in the frame, said dogs adapted to engage the cartridges in the magazine, and means for opening and closing the gun whereby the locking 35 bolt is actuated releasing one of the dogs in its movement as the gun is opened and engaging the other dog, thereby releasing the cartridge from the magazine, and the first named dog adapted to engage the next succeeding cartridge, and upon the closing of 40 the gun the locking bolt passes over the dogs releasing the last named dog and engaging the first named dog thereby releasing the cartridge which is engaged by the last named dog which has just been released by the locking bolt.

6. In a magazine gun, a frame, a magazine, a breech bolt, a locking bolt, two dogs arranged side by side in the frame and operating 50 as cartridge stops, one of said dogs projecting slightly in advance of the other, and means arranged between said dogs and arranged to move in one direction to release one of said dogs and in the other direction to release the other of said dogs, and a carrier coacting with said dogs during the 55

transit of a cartridge from the magazine to a position in front of the breech block.

7. A magazine gun comprising a frame, a locking bolt therein, dogs mounted on the frame, said dogs adapted to engage the cartridges in the magazine, and means for opening and closing the gun whereby the locking bolt is actuated releasing one of the dogs in its movement as the gun is opened and 60 engaging the other dog, thereby releasing the cartridge from the magazine, and the first named dog adapted to engage the next succeeding cartridge, and upon the closing of the gun the locking bolt passes over the 65 dogs releasing the last named dog and engaging the first named dog thereby releasing the cartridge which is engaged by the last named dog which has just been released by the locking bolt, and means for operating 70 the last named dog whereby the cartridges may be removed from the magazine.

8. In a repeating firearm, a breech frame, action mechanism therein, means for operating said action mechanism, a magazine, a 80 normally closed cut-off therefor mounted on said frame, means for opening said cut-off by the movement of the action-operating means, and means independent of said action and action-operating means for manually 85 opening said cut-off to release cartridges from the magazine independently of the operation of the action mechanism.

9. In a repeating firearm, a magazine, a cut-off comprising two pivoted parts arranged side by side, a stop abutment on each part, means for operating one part from one end to withdraw the stop abutment thereon, means for operating the other part from the other end to withdraw said abutment thereon. 90

10. In a repeating firearm, action mechanism, a magazine, a cut-off mounted independently of the action mechanism, means for mechanically actuating said cut-off simultaneously with the operation of the action 100 mechanism and by the movement thereof, and independent manually controllable means for operating said cut-off independently of the action mechanism to release the cartridges from the magazine. 105

In testimony whereof I have signed my name to this specification in the presence of two subscribing witnesses.
